UNITED STATES PATENT OFFICE.

LEONARD A. YOUNG, OF DETROIT, MICHIGAN.

BRACE FOR SPRING STRUCTURES.

1,085,232.

Specification of Letters Patent. Patented Jan. 27, 1914.

Application filed November 4, 1913. Serial No. 799,102.

To all whom it may concern:

Be it known that I, LEONARD A. YOUNG, a citizen of the United States of America, residing at Detroit, in the county of Wayne 5 and State of Michigan, have invented certain new and useful Improvements in Braces for Spring Structures, of which the following is a specification, reference being had therein to the accompanying drawings.

10 This invention relates to a brace for a spring structure and to an arrangement thereof whereby the structure as a whole may readily be brought into proper position and stayed, and whereby a portion of the 15 rim frame that undergoes the hardest usage of any part of the structure is reinforced to successfully resist deformation.

The invention consists in the matters hereinafter set forth and more particularly 20 pointed out in the appended claims.

In the drawings, Figure 1 is a plan view of a spring structure provided with a brace that embodies features of the invention; Fig. 2 is a view in end elevation thereof; Fig. 3 25 is a view in detail of the brace member; Figs. 4 and 5 are views in detail of one method of securing the springs in position; Fig. 6 is a view in detail showing the application of a spring to the rim frame; and Fig. 7 is 30 a view in detail of a slight modification of the brace holding means.

Referring to the drawings, a base 1 of any suitable design and construction carries upright body springs 2, the outer of which 35 support an upper or rim frame 3. The latter may be held in place by a suitable clip 4 or the like. As herein illustrated the base frame includes U-shaped side strips 5 and body strips 6 between whose flanges the base 40 turns 7 of the body springs are inserted and secured by clenching down the edges. A brace member connects the front side 8 of the rim frame 3 with the base frame near the back margin of the latter. As herein 45 shown the brace is formed of a bar having a central body portion 9 that rests on the upper coils 10 of the body springs adjacent the member 8 of the rim frame, and that has depending portions 11 at each end terminating in rearwardly extending obliquely disposed arms 12. The end portions 13 of the arms are turned back and are secured to the adjacent body strip 6. Where the latter are of the U-shape construction herein 55 shown this is conveniently accomplished by clenching down the flanges around the parts

13 after moving the brace to a position where the abutment of the parts 11 against the frame member 8 holds the latter in proper aligned position with the base frame. Where 60 the base frame is of different construction any suitable form of holding means may be employed to secure the end portions of the brace thereto. The same clips which secure the upper turns 10 of the body springs to the 65 member 8 of the rim frame may be made to encircle and grip the bar 9 of the brace desired. With either construction the parts 11 of the brace form shoulders against which the rim frame abuts while the body 9 of 70 the brace lies against the member 8 and reinforces it along the middle of the seat where the most pressure and weight comes and where force is frequently applied in pushing the structure back to position as in a 75 vehicle seat or the like.

Obviously, changes in the details of construction may be made without departing from the spirit of my invention and I do not care to limit myself to any particular 80 form or arrangement of parts.

What I claim is:—

1. In a spring structure having a base frame and a rim frame yieldingly supported thereon by body springs, a brace comprising a bar bent between its ends with a body portion lying on the coils of the springs adjacent the front of the rim frame and with rearwardly extending arms secured at the lower extremities to the body frame, the 90 brace having off-sets between the body and arms that transmit the thrust of the brace to the rim member.

2. In a spring structure, a base, upright body springs thereon, a rim frame carried 95 by the body springs, and a brace bent between its ends to provide a body portion resting on the upper coils of the springs back of the front member of the rim frame with rearwardly extending arms secured to 100 the body by off-sets that bear against the rim frame, the ends of the arms being attached to the base frame at a distance from the front margin thereof.

3. A spring structure comprising a base, 105 U-shaped strips in the base body springs whose base coils are secured between the flanges of adjacent strips, the flanges being compressed to retain the coil, a rim frame mounted on the body springs and a brace 110 abutting the front portion of the rim frame and resting on the upper coils of the body

spring, the lower extremities of the brace being secured to the base members at a distance back from the front margins of the base.

- 5 4. A spring structure comprising a base having strips with parallel marginal flanges, body springs whose base turns are inserted between the flanges of the strips, the flanges being bent to retain the springs, an upper
- 10 rim frame supported by the body springs, and a brace whose lower extremities are inserted between the flanges of base strip members which are compressed to retain them and whose middle portion bears against
- 15 the front part of the rim frame and rests on the upper turns of the body springs, the brace having off-sets at the ends of the body portion that form bearings to transmit thrust to the rim frame.
- 20 5. A spring structure comprising a base,

body springs mounted thereon in regular order, a rim frame secured on the upper coils of the body springs and a brace having a pair of substantially parallel arms connected by an off-set body portion, the body portion resting on the coils of the springs supporting the front margin of the rim frame, and the extremities of the arms being attached to the base frame, the distance between the arms being less than the distance between the outer portions of the coils supporting the body portions whereby the springs retain the brace from upward movement.

In testimony whereof I affix my signature in presence of two witnesses.

LEONARD A. YOUNG.
